US00D920504S

(12) **United States Design Patent** (10) **Patent No.:** **US D920,504 S**
(45) **Date of Patent:** **** May 25, 2021**

(54) **VALVE**

(71) Applicant: **Medline Industries, Inc.**, Northfield, IL (US)

(72) Inventors: **Lisa Bauer**, Buffalo Grove, IL (US); **Luke Stevens**, Wildwood, IL (US); **Michael Turturro**, Arlington Heights, IL (US); **Paulina Lowkis**, Barrington, IL (US); **Morgan Uridil**, Evanston, IL (US); **Douglas Komandt**, Chicago, IL (US)

(73) Assignee: **Medline Industries, Inc.**, Northfield, IL (US)

(**) Term: **15 Years**

(21) Appl. No.: **29/696,798**

(22) Filed: **Jul. 1, 2019**

(51) LOC (13) Cl. **24-02**

(52) U.S. Cl.

USPC **D24/129**

(58) **Field of Classification Search**

USPC D24/127-131, 112-114, 133, 186; 606/181, 185; 604/264, 523-528, 272, 604/187, 158, 164.01-164.11, 181, 184, 604/227; 600/101, 139, 143; 128/200.24, 207.14, 207.15

CPC B65D 83/425; B65D 83/14; A61M 25/065; A61M 5/42; A61M 25/0612; A61M 25/00; A61M 39/00; A61M 27/00; A61M 25/0043; A61M 25/0067; A61M 25/0097; A61F 2/958

(57) **CLAIM**

The ornamental design for a valve, as shown and described.

DESCRIPTION

FIG. 1 is a front, top perspective view of a valve in accordance with our new design;

FIG. 2 is a rear, bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines depict portions of the valves that form no part of the claimed design.

1 Claim, 7 Drawing Sheets
